BARREL CLOSURE

John S. Townsend, Chicago, Ill., assignor to Wilson & Bennett Manufacturing Company, Chicago, Ill.

Application March 10, 1934, Serial No. 715,027

5 Claims. (Cl. 220—61)

This invention relates to closures for barrels of the type more or less commonly known as "full open top" in which the head or cover is secured to the top of the barrel by means of a clamping ring, and is particularly directed to the construction of such clamping ring and means for operating the same.

Heretofore split rings have been proposed or used, such rings having links and levers for drawing the ends together but these have been found objectionable for various reasons. For instance the rings are often stuck to the barrel on account of adhesive material which may collect thereon when the barrel is filled with such material. Or in some instances the rings and adjacent portions of the barrel may become jammed in shipping so that it makes it difficult to remove the rings. When the ends of the rings are permanently connected as by means of rings it is only possible to permit a relatively slight opening between the ends of the rings so that it is difficult to release the entire ring from the head.

In accordance with the present invention I provide closing or fastening means which does not make a permanent connection between the ends of the rings but which may be released so that the ring may be freely sprung open either for the purpose of placing the same on the barrel or removing the same therefrom.

Other objects of this invention are to provide an improved closing ring which may be readily constructed and which may be particularly durable and efficient in operation; to provide a barrel closing ring having a closing arm or arms detachably connected with one portion of the ring; to provide a ring of this character with a combined closing and fastening device which will also serve for forcing the ring open; and to provide such other advantages and improvements as will appear from the following description taken in connection with the accompanying drawing in which

Figure 1 is a plan view of a barrel with my improved closure applied thereto;

Figure 2 is an enlarged detail of the double acting, or combined closing and opening mechanism;

Figure 3 is a sectional view or front view of the parts shown in Figure 2;

Figure 4 is a sectional view taken on the line 4—4 of Figure 2; and

Figure 5 is a sectional view taken on the line 5—5 of Figure 1.

The barrel 6 which may be of any ordinary or preferred form of construction is provided with

the usual bead 7. The cover 8 has a depressed portion fitting within the top of the barrel and an annular flange 9 which extends out over the bead 7 and which may be provided with a gasket 10 when a tight closure is desired. The ring 11 is substantially semi-circular in cross section or provided with converging inner surfaces for engagement with the bead and flange respectively for drawing these parts closely together when the ring is made tight.

A lifting plate or supporting member 12 is welded or otherwise secured to the upper inner edge or flange of the ring 11, as shown in Figures 1 and 5, preferably at a point opposite to the split or at some distance therefrom. This plate assists in applying the ring to the cover as it will prevent the ring from slipping down over the flange when it is being applied and furthermore serves as a convenience in lifting the ring from the barrel.

Two brackets or projections 13 and 14 are welded or otherwise secured to the inner edge of the upper flange of the ring 11 adjacent to the split or opening 15. These brackets serve to carry and cooperate with the closing mechanism and extend inwardly and downwardly so that no parts of the closing mechanism extend above the upper surface of the ring. This is an important feature as it facilitates the handling and stacking of the barrels. The bracket 13 has a bifurcated bearing 16 at its inner end for receiving one end of an operating lever 17 which is pivotally secured thereto by a pivot 18. This lever is bent to conform generally with the shape of the barrel head as shown in Figure 1 and its outer end may be held in fastening position by means of any suitable catch 19 secured to the ring 11.

The inner portion of the bracket 14 is bent downwardly or offset as shown in Figure 3, in order to bring it in substantial horizontal alignment with the lever 17. The inner end of this bracket is provided with an irregularly shaped recess or opening 20.

The lever 17 is provided with a double purpose or combined pulling and pushing arm which co-acts with the bracket 14 for drawing the ring to closing position and also for forcing the ring open. In the particular form shown this arm is formed of two bars 21 and 22 which are pivoted at 23 to the lever and which have their central portions spread or offset as shown in Figure 3 to straddle the bearing at the inner end of the bracket 13. The outer or free ends of the bars are connected by a pin or rivet 24 which is adapted to engage with the hook-like end or recess 20

of the bracket 14. One side 25 of the recess 20 is curved to form a bearing for receiving the pin 24 for the closing operation. The recess preferably extends outwardly and has another bearing portion 26 for receiving the pin for the loosening or opening operation. The bracket may also have a further notch 27 at its inner end for receiving the pin for spreading the ends of the ring still further apart.

10 When the ring is to be applied the pin 24 is disengaged from the bracket 14 leaving the ends free so that they may be spread apart to permit the ready application of the ring to the barrel cover and bead as shown in Figure 4. During 15 this movement the plate 12 serves as a stop as shown in Figure 5, to prevent the ring from falling down over the flange and thus expedites the application of the ring to the barrel. When the ring has been placed in position the lever 17 is 20 swung forwardly so that the pin 24 may be brought into engagement with the bearing 25 in the bracket 14. Then by swinging the lever outwardly or to closing position as shown in Figure 1, the ends are drawn together and the cover is 25 pressed closely to closing position. When the lever is swung to its extreme position it may be fastened by the catch 19.

When the cover is to be removed the lever 17 is again swung forwardly as indicated by the dotted lines in Figure 2 and the pin 24 will engage with 30 the bearing 26 to force the corresponding end of the ring outwardly and thus to release the same. Ordinarily this initial releasing movement will be sufficient and the pin may be moved out of engagement with the recess which will 35 permit the operator to grasp the ends of the ring and pull it off from the barrel. However if the initial spreading movement is not sufficient the pin may be moved out of the recess 20 and brought into engagement with the outer portion 40 of the bracket, and another movement of the lever will cause the further spreading of the ends of the ring. As above suggested this provision for opening the ring is of particular importance 45 where the ring has been stuck on as by paint or the like, or has been jammed in transportation so that it is difficult to remove the same.

Having thus described my invention, what I claim and desire to secure by Letters Patent is:

50 1. A new article of manufacture comprising a split closing ring for barrels having a bracket extending inwardly at one end of the ring, a bifurcated bearing at the inner end of the bracket, a lever having one end pivoted in said bearing, a second bracket adjacent to the other end of the

ring having a recess at the inner end thereof, bars pivoted to the lever at a short distance from said bearing, said bars being offset to straddle the bearing, and a pin between the outer ends of said bars adapted to engage with the recess in the second bracket.

5 2. A split closing ring of the character set forth having upper and lower faces and having an inwardly projecting bearing adjacent to one end thereof, a lever pivoted to said bearing and adapted to swing in a plane parallel to the face of the ring, an arm pivoted to the lever and adapted to project beyond the bearing, a bracket on the opposite end of the ring having a recess at its inner end, and means on the arm for engaging with the recess, the walls of said recess providing oppositely disposed abutments serving to retain said last mentioned means in said recess during contraction and expansion of the ring, and no part of such operating devices extend above or below the upper or lower faces of the ring.

10 3. A split contractible barrel closing ring in the form of a channel opening inwardly towards the plane of the ring, means coacting with the 25 ends of the ring for contracting the same, said ring having a ledge extending inwardly from the upper edge thereof, and positioned substantially on the opposite side of the ring from the contracting means and serving as a stop when placing the ring in position.

15 4. The combination with a split closing ring for a barrel, of brackets secured to the ends of the ring and extending inwardly and downwardly, a closing lever pivoted to one of said brackets, 35 said lever being curved to conform to the inner curvature of the cover, parallel arms pivoted at one end to said lever, a pin connecting the opposite ends of said arms, said pin being adapted to engage with a recess in the second named 40 bracket for the purposes described.

20 5. The combination with a metallic receptacle having a bead rolled about its open end, and a removable cover for said receptacle having a marginal flange fitting over the said bead, of a 45 split contractible channeled clamping ring having walls engageable with the flange and bead for pressing the same together when the ring is contracted, inwardly extending lugs adjacent the ends of said ring, a lever for contracting said ring pivoted to one of said lugs, the other of said lugs having a notch therein, a link pivoted to the lever and carrying a pin at its other end for engagement with said notch.

JOHN S. TOWNSEND.
